UNITED STATES PATENT OFFICE

JOHN Q. SHERMAN AND ALBERT W. METZNER, OF DAYTON, OHIO, ASSIGNEES, BY DIRECT AND MESNE ASSIGNMENTS, TO THE STANDARD REGISTER COMPANY

MANIFOLDING MACHINE

Application filed May 18, 1926. Serial No. 109,991.

Our invention relates to machines for use in making manifold copies on printed forms, in the form of long webs, and in which the webs are folded into a bundle or flat pack, of 5 the area generally of a single form, being folded occasionally in two or three form length folds when the individual forms are very short in length.

Preferably our invention is used with 10 multiple flat pack, printed webs, in which two or more are first brought into registry with each other and then folded into a single bundle.

In the manifolding of large sized forms, 15 and in machines which are called upon to handle a large number of forms, it is quite a problem to provide for the proper storage of large quantities of the webs in such a way as to furnish evenly moving, but mutually ad- 20 justable plural webs of paper.

Our invention is directed chiefly to the provision of a manifolder in which the usual type of paper supporting and feeding mechanism may be employed, but in connection 25 with which means are provided for mounting in alignment with the paper manipulating parts, a container in which is held the plural webs in the folded pack, and which extends far below the regular register base, for the 30 purpose of holding larger quantities of printed forms than can be held by the regular register cabinet.

Preferably we provide a single metal container, having means for mounting it in true 35 position in connection with the paper manipulating machine elements, and preferably having means for side charging the said container so that a large sized bundle of the dimensions of the container, can be set in place 40 through the side thereof.

Preferably, also, we drop the container into the machine from above, or hook it in place from below, gaining thus the advantage 45 that the orifice, into which the container drops, and by means of which it may be suspended, if desired, automatically gives the true alignment of the paper with the paper feeding and supporting devices.

It is of importance in connection with ma-

chines using marginally apertured paper, and pin wheels as feed means, which is the type of machine we illustrate, and in many other types of paper feeds also, that the paper webs be delivered in a true alignment with 55 the feeding devices. When the paper storage gets out of line, the paper gets torn in the feed, or does not move through it regularly and evenly, and gets out of alignment. This alignment of delivery is of importance in 60 flat pack machines, for the reason that unlike machines using paper rolls and spindles, there is nothing that serves to align the paper packs except the containers in which they are placed.

We accomplish our objects by that certain construction and arrangement of parts to be hereinafter more specifically pointed out and claimed.

In the drawing:—

Figure 1 is a side elevation of a typical machine illustrating the invention.

Figure 2 is a detail central longitudinal vertical section of the frame of the machine.

Figure 3 is a section on the line 3—3 of 75 Figure 2.

Figure 4 is a plan view of the paper feed and support.

Figure 5 is a perspective of the preferred type of box for holding the paper.

It will be understood that the type of paper pack which we employ is formed of a number of long webs of paper which are registered with each other and folded back and forth into a flat pack, of the area generally 85 of a single printed form. Such packs are bulky in size, and heavy, if sufficient forms for a conveniently long period are provided. They are known in the trade as superfolded flat packs, meaning that a number of forms 90 are folded together in registry.

The machine shown is formed as a table having legs 1, and a top 2, with a fall board about the top as at 3. The top 2 may take the place of the base of a manifolding register, of which any type may be used. The side frames of such a register are shown at 4 and 5, the latter being full height and the former being cut down intermediate the two ends thereof.

The top 2 is cut away between the two side frames, and from beneath the feeding point forward to the front edge of the top. Leaves 6 and 7 are turned up at the front and back 5 of this opening (Figure 2). Also to strengthen the side frames, pieces 8 are secured underneath the edges of the opening at the sides and bent up alongside the side frames.

10 The structure now described provides for a rectangular opening in the base of the manifolder, or top of the supporting table, however, it be regarded, with four walls of strong construction, the whole being simply 15 formed from sheet metal and the parts united in any convenient way.

This opening is of the size of the flat pack container or box which will be described.

To briefly outline the remainder of the 20 essential parts of a typical manifolding machine, we have shown the writing table or support, formed of a plate 9, secured on a pair of hinge arms 10, 10, which are supported at the front edge of the side frames.

25 The arms have idler rolls 11, held between them as guides for the several webs of the superfolded flat pack. The writing table rests on lugs on the side frames when swung down in place, and has clearance slots 12, for feeding device in the shape of pin wheels 13, shown as being operated by a feed handle 14.

A hinged bar which holds the paper down on the pin wheels is illustrated at 15, and a cover 16 is shown as hinged to the back end 30 of the machine base, which encloses the entire upper mechanism.

The primary object of our invention is the provision of an automatically aligned, simply 40 installed and jumbo sized superfolded flat pack of paper webs. We provide for this by the use of the orifice in the base under the table top, and a box illustrated best in Figure 5.

The box is shown as having side walls 17, 45 three in number, and a partial width side opening hinged wall 18, which is hinged at 19 to the base of the box. The top of the box may be left entirely without closure. To brace the top, where the hinged wall is 50 located, we provide an angle bar 20, which is secured to form the top corner of the box, and incidentally provide a hand hold, for lifting. A handle 21 is secured to the opposite wall of the box.

55 Welded to the back wall and to the hinged wall of the box, are the brackets 22, by means of which the box is suspended in the register base under the table top. It will be understood that the box might be supported, 60 however, on a shelf below the base and table top.

In use the hinged wall of the box is opened and a pack of paper inserted. The cover of the machine is swung up and the writing 65 support also elevated. The box can then be

dropped in, and the box will be held suspended by the brackets on the front and back leaves 6 and 7. This securely and automatically places the paper in alignment with the rest of the machine, since the box will be of a size to hold the superfolded pack. If desired, compartments could be made in the box, for a plurality of single packs, or a smaller size box provided with an adapter to fit within the opening in the base of the machine, and engage the supporting leaves. 70

75 By reference to printed forms in the claims, we refer to that portion of the web which forms the area of a single fold in the web.

Having thus described our invention what 80 we claim as new and desire to secure by Letters Patent, is:—

1. In a manifolding machine for use with webs of paper with forms printed thereon folded into a bundle of a restricted area, said 85 machine having a movable writing support, and a paper feed therefor, the combination of a frame for mounting said support and feed, having an opening below said writing support, a box of the size of said opening, adapted 90 to retain a paper bundle of the type noted, and means for supporting said box in said opening, whereby said paper will be properly aligned by the walls of said opening.

2. In a manifolding machine for use with webs of paper folded into a bundle of the area of a printed form on said paper, said machine having a movable writing support, and a paper feed therefor, the combination of a 95 frame for mounting said support and feed, having an opening below said writing support, a box of the size of said opening, adapted 100 to retain a paper bundle of the type noted, and means for supporting said box in said opening, whereby said paper will be properly aligned by the walls of said opening, said box having four side walls, one of which is 105 movable for the purpose of charging the box with paper from the side.

3. In a manifolding machine for use with webs of paper folded into a bundle of the area of a printed form on said paper, said machine having a movable writing support, and a paper feed therefor, the combination of a frame for mounting said support and feed, having an opening below said writing support, a box of the size of said folded forms, 110 adapted to retain a paper bundle of the type noted, and means for supporting said box in proper position in said opening, whereby said paper will be properly aligned with the feeding mechanism, said means comprising hooks on the box to engage the walls about said opening. 115

4. In a manifolding machine for use with webs of paper folded into a bundle of the area of a printed form on said paper, said machine having a movable writing support, and a paper feed therefor, the combination of a frame for mounting said support and feed, 120

having an opening below said writing support, a box of the size of said opening, adapted to retain a paper bundle of the type noted, and means for demountably supporting said box in said opening, whereby said paper will
5 be properly aligned by the walls of said opening.

JOHN Q. SHERMAN.
ALBERT W. METZNER.
